ELECTRIC IGNITION SYSTEM

William H. Maycock, Coventry, England, assignor to General Electric Company, a corporation of New York

Application October 18, 1939, Serial No. 300,065
In Great Britain October 18, 1938

6 Claims. (Cl. 123—148)

This invention relates to an electric ignition system for an internal combustion engine and more particularly to an electric ignition system for starting an internal combustion engine.

5 Heretofore the starting of an internal combustion engine which has a magneto to provide the electric ignition has been accomplished through the use of an auxiliary hand-turned or motor-turned magneto or by a battery operated 10 trembler coil. The high voltage induced in the secondary windings of the starting ignition arrangement is fed through a trailing electrode on the main magneto distributor brush holder, and is then distributed to the appropriate distributor 15 electrode so as to provide a spark at the spark plug for starting purposes.

An object of my invention is to provide an improved ignition arrangement for starting an internal combustion engine.

20 A further object of my invention is to impress a voltage of varying magnitude on the primary winding of a magneto to provide the necessary electric ignition for starting an internal combustion engine.

25 Further objects and advantages of my invention will become apparent from the following description referring to the accompanying drawing, and the features of novelty which characterize my invention will be pointed out with particularity in the claims annexed to and forming a part of this specification.

In the drawing, Fig. 1 diagrammatically illustrates a magneto ignition circuit provided with an embodiment of my improved starting arrangement; Fig. 2 is a modification of the starting arrangement shown in Fig. 1; and Fig. 3 is a modification of the starting arrangement shown in Fig. 2.

Referring to the drawing, in Fig. 1 I have illustrated diagrammatically a conventional magneto ignition system including a magneto 10 having a core member 11 with a primary winding 12 and a secondary winding 13 wound thereon. To provide the necessary cyclic interruption in the magneto primary circuit the primary 12 has shunted across it a breaker 14 and a capacitor 15. The secondary winding 13 is in circuit with the conventional distributor 16 and spark plug 17. Only one spark plug is shown 50 but, of course, it is to be understood that there is one in circuit with each one of the distributor segments. A rotatable member is arranged to provide the field excitation for the magneto and includes permanent magnet pole pieces 18 which 55 are magnetically connected with the primary and

secondary windings through the core member. The rotatable member, of course, is connected to the crank-shaft of the internal combustion engine either directly or through suitable gears, and upon rotation thereof a current will be induced in the primary winding 12. Upon the interruption of the primary winding circuit by the breaker 14 which is operated by the crank-shaft either directly or by means of suitable gears through the cam member 19, a voltage will be induced in the 10 secondary winding 13 at the time the rotating brush of the distributor 16 is opposite a proper segment. Sufficient voltage to operate the plug 17 will only be obtained when a speed faster than starting or cranking speed is reached due to inherent characteristics of the magneto circuit. It is, of course, to be understood that any dynamo-electric machine of the magneto type may be used which is designed to produce the desired voltage in the secondary circuit for the particular 20 engine with which it is to be used.

It is therefore apparent from the above description that a magneto cannot produce the desired ignition until its rotatable member has begun to rotate at a speed faster than starting 25 speed. Since this rotation is caused by the engine through its crank-shaft it is obvious that some auxiliary arrangement must be used to produce the ignition during the starting of the engine. I provide the desired ignition during starting by impressing a suitable voltage of varying magnitude on the primary winding of the magneto. In the circuit diagram shown in Fig. 1 this voltage which may be from a source of alternating current is connected across the terminals 30 20 and 21. This voltage may be produced in any desired manner, and in Fig. 2 I have shown a simple and effective arrangement which includes a coil in circuit with a unidirectional potential. The energy source of this voltage includes a battery 22 across which is connected a trembler device which includes an inductance or coil 23 and an interrupter having contacts 24 and 25. In order that there may be provided a pulsating voltage across the inductance or trembler coil, 35 the coil is connected to the battery through the contacts 24 and 25. The contact 25 is carried by an armature 26 which is adapted to cooperate with the core member 27 of the trembler coil and the contact 24 is held stationary. Thus when the 40 switch 28 is closed current will flow through the contacts 24 and 25 to the trembler coil. This flow of current will set up a magnetic field which attracts the armature and opens the contacts. A suitable capacitor 29 may be placed across these 45 50 55 60 65 70 75 80 85 90 95 100

contacts so as to minimize arcing. When the contacts open the direct current stops flowing in the trembler coil and the magnetic field begins to subside. Since the armature is biased towards 5 the stationary contact 24, the contacts will close and direct current will again flow through the trembler coil. This opening and closing of the contacts will continue and a pulsating voltage will therefore appear across the trembler coil. In 10 order to prevent disastrous results to the permanent magnets in the magneto in case the contact 15 and 26 should be stuck closed, I provide a capacitor 30 in the connection 31 between the trembler coil and the primary winding of the magneto. This connection may also be provided 20 with an isolating switch 32. The other side of the trembler coil is connected to the other side of the primary winding of the magneto through the connection 33. This side of the primary 25 winding also may be grounded so as to form a return path from the spark plug. Since a pulsating voltage appears across the inductance or trembler coil a pulsating current will flow through the capacitor 30 to one side of the primary winding 30 and through the primary winding of the magneto back to the trembler coil. It may readily be seen, therefore, that the current flowing through the primary will induce an alternating current voltage in the secondary which will cause 35 a current to flow through the distributor to a spark plug causing a spark. A spark is only desired when the magneto breaker contacts are open so that ignition will occur at the proper time. As these contacts, when closed, are a much lower impedance path to the current than the primary winding, the pulsating current will flow through the primary winding only when the contacts are open, thus providing a spark at only the proper time. When the internal combustion 40 engine comes up to speed the isolating switch 32 may be opened so as to disconnect the starting circuit from the primary of the magneto and the ignition will then be provided by the magneto.

In the modification shown in Fig. 3 a circuit is 45 shown similar to that illustrated in Fig. 2 except that the condenser 30 is placed between the grounded side of the primary winding and the trembler coil. This circuit may be used when grounding of the battery is not desired. The 50 starting circuit, however, will operate similarly to that described in relation to Fig. 2.

In view of the foregoing it will be seen that I 55 have provided a new and improved ignition arrangement for starting an internal combustion engine which makes use of the conventional magneto which provides the ignition after the engine has been started.

Modifications of the particular arrangements 60 which I have disclosed embodying my invention will occur to those skilled in the art, so that I do not desire my invention to be limited to the particular construction set forth and I intend in the appended claims to cover all modifications which 65 do not depart from the spirit and scope of my invention.

What I claim as new and desire to secure by Letters Patent of the United States is:

1. An ignition system for an internal combustion engine including a magneto having a primary and a secondary winding and an excitation means made effective by the rotation of the engine crank-shaft to induce a current in said primary winding, a breaker having electrical connection with said primary winding and being so 70 constructed and arranged as to be periodically

actuated by the rotation of the engine crank-shaft so that a voltage will be induced in said secondary winding, a source of unidirectional potential, a trembler device, means for connecting said trembler device across said source, and 5 means for connecting said trembler device across said primary winding so that ignition is provided for the engine during starting, said trembler device being short circuited by said breaker by the closing of its contacts when an ignition spark is 10 not desired.

2. An ignition system for an internal combustion engine including a magneto having a primary and a secondary winding and an excitation 15 means made effective by the rotation of the engine crank-shaft to induce a current in said primary winding, a breaker having electrical connection with said primary winding and being so constructed and arranged as to be periodically actuated by the rotation of the engine crank-shaft so that a voltage will be induced in said secondary winding, a source of unidirectional potential, an inductance, means for connecting said inductance across said source, means for connecting said inductance across said primary 20 winding, and means for causing the periodic interruption of said circuit including said source and said inductance so that ignition is provided for the engine during starting, said inductance being short circuited by said breaker by the closing of its contacts when an ignition spark is 30 not desired.

3. An ignition system for an internal combustion engine including a magneto having a primary and a secondary winding and an excitation 35 means made effective by the rotation of the engine crank-shaft to induce a current in said primary winding, a breaker having electrical connection with said primary winding and being so constructed and arranged as to be periodically 40 actuated by the rotation of the engine crank-shaft so that a voltage will be induced in said secondary winding, and a circuit including a source of unidirectional potential and a coil, said coil having electrical connection with said primary winding through a capacitor, and means 45 for causing the periodic interruption of said circuit so that ignition is provided for the engine during starting.

4. An ignition system for an internal combustion engine including a magneto having a primary and a secondary winding and an excitation means made effective by the rotation of the engine crank-shaft to induce a current in said primary winding, a breaker having electrical connection with said primary winding and being so 55 constructed and arranged as to be periodically actuated by the rotation of the engine crank-shaft so that a voltage will be induced in said secondary winding, and a circuit including a battery and a coil, said coil having electrical connection with said primary winding through a capacitor and an isolating switch, and means for causing the periodic interruption of said circuit so that ignition is provided for the engine 60 during starting.

5. An ignition system for an internal combustion engine including a magneto having a primary and a secondary winding and an excitation means made effective by the rotation of the engine crank-shaft to induce a current in said primary winding, said primary winding having one side thereof connected to ground, a breaker having 70 electrical connection with said primary winding and being so constructed and arranged 75

- as to be periodically actuated by the rotation of the engine crank-shaft so that a voltage will be induced in said secondary winding, and a circuit including a battery and a coil, said coil having electrical connection with said primary winding, and means for causing the periodic interruption of said circuit so that ignition is provided for the engine during starting, said grounded side being connected to said coil through a capacitor.
6. An ignition system for an internal combustion engine including a magneto having a primary and a secondary winding and an excitation means made effective by the rotation of the engine crank-shaft to induce a current in said pri-

mary winding, a breaker having electrical connection with said primary winding and being so constructed and arranged as to be periodically actuated by the rotation of the engine crank-shaft so that a voltage will be induced in said secondary winding, and a circuit including a battery, an interrupter and a coil, said coil having electrical connection with said primary winding through a capacitor, and said interrupter being so constructed and arranged as to be periodically actuated by the current flowing through said coil so that ignition is provided for the engine during starting.

WILLIAM H. MAYCOCK.
